UNITED STATES PATENT OFFICE.

ARCHIBALD S. CUBITT, OF PITTSFIELD, MASSACHUSETTS, ASSIGNOR TO GENERAL ELECTRIC COMPANY, A CORPORATION OF NEW YORK.

ELECTRIC HEATER.

1,077,676.

Specification of Letters Patent.

Patented Nov. 4, 1913.

Application filed September 21, 1910. Serial No. 583,023.

To all whom it may concern:

Be it known that I, ARCHIBALD S. CUBITT, a subject of the King of Great Britain, residing at Pittsfield, county of Berkshire, State of Massachusetts, have invented certain new and useful Improvements in Electric Heaters, of which the following is a specification.

This invention relates to electric heaters and has for its object the provision of an improved self-contained electric heating unit which may be used either separately or combined with others to form a simple, efficient and inexpensive heater.

One of the objects of my invention is to provide a self-contained heating unit which will be simple and rugged in construction and which will be adapted to a variety of uses either singly or in combination with other units of similar construction.

Another object of my invention is to provide an electric heater which is composed of sections, each section being a self-contained heating unit, the arrangement being such that any desired number of the sections may be combined to form a heater of any desired size or capacity.

In carrying out my invention I form a unit by securing a resistance conductor to an elongated support which partially encloses the conductor. In one form of my invention I provide an elongated trough which may be U-shaped or channel shaped in section and secure a resistance conductor 30 wound into a spiral centrally within the trough but out of direct contact therewith. This trough may be conveniently made by bending a strip of metal into the desired form and enameling the metal either before or after the bending operation. The resistance spiral is supported at intervals throughout its length and electrical connections are made at the ends of the spirals. The units may be placed side by side and secured together so as to provide a plurality of parallel resistance spirals which are separated from each other by the sides of the troughs. Any desired number of these units may be secured together; and thus any size 45 or capacity of heater may be formed.

Other objects and purposes of my invention will appear in the course of the following specification, in which I have shown

my invention embodied in concrete form for purposes of illustration.

In the drawing illustrating one form of my invention, Figure 1 is a perspective view of a portion of my heating unit; Fig. 2 is a fragmentary sectional view of the same; Fig. 3 is a perspective view of one of the supporting members; and Fig. 4 is a perspective view of a heater formed of a plurality of units.

Referring to the drawings, 10 represents a support for the resistance conductor. This support is made in the form of an elongated channel shaped trough. This trough may be, and preferably is made of enameled metal, since the metal is conveniently bent in desired form and the enamel affords electrical insulation and likewise prevents rusting, etc. Within this trough 10 I secure the resistance conductor 11, which conductor is shown in the form of a spiral extending substantially throughout the length of the trough. The spiral is supported at intervals by supporting members 12. These supporting members consist of a sleeve portion 13 through which the spiral passes and a shank 14 which passes through the web member 15 of the channel shaped trough. The end of the shank is split so as to provide wings 16 which are bent down to secure the member in place. The metal of the trough is pressed inward at 17 around the hole for receiving the supporting member and an insulating sleeve 18 is fitted in the depression. An insulating washer 19 is on the inner side of the depression. The shoulders 20 on the supporting member bear against the washer 18 and when the wings 16 are bent down, as shown in Fig. 2, the support is held securely in place. The supporting member is thus insulated from the metallic trough and the enamel coating of the trough is not depended upon for the necessary insulation. The ends of the spiral are connected to terminals 21 which are secured in place by bolts 22. The spiral is supported substantially midway of the trough and it is enclosed on three sides. The trough provides a pocket for the accumulation of heated air and to a certain extent prevents the circulation of air over the conductor to cool it.

In Fig. 4 I have shown a number of these units united so as to form a heater. The

units are placed side by side and secured together by a strip 22. It is obvious that the number of these strips 22 for holding the units together will depend upon the length 5 of the unit. The ends of the spirals in the adjacent troughs are connected together by connectors 23. These connections may be made so that all of the spirals will be in series, or in any manner desired. By the 10 employment of my invention any desired size or capacity of heater may be obtained by combining a suitable number of sections.

My invention will be found useful in 15 connection with ovens, broilers and the like where it is desired that the unit be accessible and at the same time protected. By spacing the resistance conductor from the support, a more uniform heating of the support is produced. The same unit may be 20 employed for various sizes of ovens and broilers by simply increasing and decreasing the number of units.

While I have described my invention as 25 embodied in concrete structure in accordance with the patent statutes, it should be understood that I do not limit my invention thereto, since various modifications thereof will suggest themselves to those skilled in the art without departing from the spirit 30 of my invention, the scope of which is set forth in the annexed claims.

What I claim as new and desire to secure by Letters Patent of the United States, is,—

1. An electric heating unit comprising a channel shaped support, an electrical resistance suspended within said support from the web member thereof, and terminals for said resistance extending through the suspending member. 35

2. An electric heating unit comprising a channel shaped support, an electrical resistance coil suspended within said support from the web member thereof, means for insulating the said coil from said support and terminals extending from said coil through 45 the suspending member.

3. A sectional electric heater comprising a plurality of channel shaped supports, each having an electrical resistance suspended within the same from the web member thereof and insulated therefrom, terminals connected to each of said resistances extending through the web members of said supports and means for mechanically connecting said 50 members together. 55

In witness whereof, I have hereunto set my hand this 16th day of September, 1910.

ARCHIBALD S. CUBITT.
